Primary Examiner — Bridget L. Eland*Assistant Examiner* — Lauren McVey(74) *Attorney, Agent, or Firm* — Philip H. Burrus, IV(57) **CLAIM**

The ornamental design for a medical gown, as shown and described.

DESCRIPTION

FIG. 1 is a front elevation view of a medical gown illustrating my new design; and,

FIG. 2 is a rear elevation view thereof.

The short-dash broken lines in the drawings represent the bounds of the claimed design. The long-dash broken lines between the neck and opening along the rear of the gown is a perforation and forms part of the claimed design. The long-dash broken lines on the front at the waist form no part of the claimed design.

The design consists of the appearance and shape of the medical gown in a flat plane with no depth or contour.
